FIG. 1

FIG. 2

Lester R. Wellman
INVENTOR.

UNITED STATES PATENT OFFICE.

LESTER R. WELLMAN, OF CHICAGO, ILLINOIS, ASSIGNOR TO FRIEDLY VOSHARDT CO.,
OF CHICAGO, ILLINOIS, A CORPORATION OF ILLINOIS.

DESIGN FOR A LAMP-BASE.

57,176.

Specification for Design.

Patented Feb. 22, 1921.

Application filed August 23, 1920. Serial No. 405,526. Term of patent 7 years.

To all whom it may concern:

Be it known that I, LESTER R. WELLMAN, a citizen of the United States, residing at Chicago, in the county of Cook and State of Illinois, have invented a new, original, and ornamental Design for a Lamp-Base, of which the following is a specification, reference being had to the accompanying drawing, forming part thereof.

I claim:

The ornamental design for a lamp base, as shown.

LESTER R. WELLMAN.
